UNITED STATES PATENT OFFICE.

J. PARKER PRAY, OF NEW YORK, N. Y.

DESIGN FOR A NAIL-TRIMMER.

SPECIFICATION forming part of Design No. 15,041, dated June 3, 1884.

Application filed December 18, 1883. Term of patent 14 years.

To all whom it may concern:

Be it known that I, J. PARKER PRAY, a citizen of the United States, residing at New York, in the county of New York and State of New York, have invented and produced a new and original Design for a Pocket-Diamond Emery-Board, of which the following is a specification, reference being had therein to the accompanying drawing.

10 My design relates to an article for toilet use for trimming finger-nails.

In the accompanying drawing the figure represents a perspective view of my design.

15 The configuration of the design consists of a thin narrow strip of any suitable material having a roughened surface and rounded ends and

parallel vertical walls on the longer sides, as shown.

What I desire to claim by Letters Patent is—

20 The design for a finger-nail trimmer herein shown and described, consisting in the thin elongated strip having a roughened surface upon its faces, the longer sides being provided with parallel vertical walls and the ends thereof being rounded.

25 In testimony whereof I affix my signature in presence of two witnesses.

J. PARKER PRAY.

Witnesses:

FRANK A. FOUTS,
JOHN T. SUTER, Jr.
